UNITED STATES PATENT OFFICE.

MAX KÖPPE, OF DRESDEN-GRUNA, GERMANY.

MACHINE FOR TURNING IN EDGES OF HIGH-GRADE LEATHER GOODS.

Application filed June 11, 1927, Serial No. 198,062, and in Germany January 30, 1926.

The invention relates to a contrivance for turning in edges of regular width when manufacturing high grade leather goods, i. e. wallets, pocketbooks, bill-folds and other goods of the portfolio industry. In the case of boots, shoes and other goods where the turned-in edge is not visible, it is not so important that the latter be absolutely regular, and the leather used in this branch 10 of industry is of such strength and permanency of form, that when the edges are skived and turned in, the whole leather piece retains the shape it had after having been cut out.

15 On the other hand, the portfolio industry employs a very soft, supple leather, to which starch paste is commonly applied in order to stiffen the leather. Before turning-in the edges, an adhesive is applied, which, however, again softens the leather to a certain degree. All these preparatory operations, especially the skiving of the leather repeatedly alter the shape of the cut-out piece, and it is necessary to trim it to the former width.

25 Up to now, the edges of such mentioned leather goods have been generally turned in by hand, remaining visible on the lined inner side of the work-piece. For this purpose a metal copy was used, the overstretched irregular leather edge being subsequently trimmed off with a knife by hand. In order to remove the metal copy, the edges had to be first raised and then pressed down again. In curved parts, a great deal depended on 30 the skill of the workman. Even if it had been possible to avoid cutting into the leather in concave parts, or, owing to compression, to avoid folds of the leather in convex parts, one could not help lifting the turned edges 35 for the purpose of removing the metal copy and pressing them down again, thereby perhaps slightly damaging the edge. The well-known bending machines generally employed in the leather industry could not satisfy the 40 requirements mentioned here and were therefore not used.

In order to attain edges of regular width and of the kind mentioned, the invention proposes an improved machine wherein co- 45 operating drums and smoothing fingers are employed to gradually turn and press an edge of the material and wherein cutting means are provided to trim the edge after it is turned.

For the purpose of avoiding folds in 55 curved parts, the turned-in leather edge resting on a well-known rotating drum acting as a support, is smoothed by means of smoothing fingers which, being close to each other and rotating with the drum, come into action 60 one after another, passing over the leather in a direction from creasing line to the free edge. Simultaneously or immediately after the smoothing action, the extreme outer edge of the leather passes on to a rotating support, 65 where it is trimmed by a circular cutter.

The smoothing fingers, protected by a case and fitted round the entire circumference of a kind of drum are, by means of a cam which may be put out of action, caused to 70 move down till they touch the turned leather edge. Hereupon, influenced by a spring, they slide over the turned edge of the leather, exerting a slight resilient pressure, and according to the curve of the edge, stretching 75 or compressing (staving) (if necessary both) the skived edge.

The smoothing fingers which are no longer in control of the cam are kept back or led back in an upright position by means of 80 springs.

The position in which the smoothing fingers exert just the right pressure on the rim is determined beforehand, and when working leather of greater thickness, it is consequently necessary to decrease the diameter of the supporting drum. This is made possible by fitting on the drum a number of 85 flat rings, one above the other. Adjustment in axial direction is, however, also necessary 90 according to the width of the turned-in edge. Similar adjustment is also of advantage for the circular cutter, the counter-cutter, and therefore also for the grinding mechanism. A flange 12 or in place of this an upright 95 roller 12^a serves as a support to the edge.

For the purpose of employing this machine for simultaneously bending and trimming edgings for rolling edges thinner, or for rolling down closing seams, operations 100 which have hitherto been effected by hand, a roller, well-known in bending machines, is here also provided. It is fixed, together with the cam, on a reversible shaft so that either the smoothing fingers or the roller can 105 be put out of action.

A contrivance as proposed by the invention can also be employed with advantage as

an edging machine in other branches of the leather industry.

In order to make the object of this invention quite clear, I have drawn a diagram of this machine as it may be constructed, and in the following describe the way it works. Arrows indicate direction of movement.

Fig. 1 is a side view of the machine.

Fig. 2 is an enlarged longitudinal section 10 through the machine on the line *a*—*b* of Fig. 3.

Fig. 3 is a section on the line *c*—*d* of Fig. 2.

Fig. 4 shows the smoothing fingers alone, 15 but out of action, because the cam has been swung back. The pressure roller is in working position.

Fig. 5 shows part of the circumference of the drum with smoothing fingers in evolution 20 together with the piece of work, the cutting device being removed.

1 is the frame of the machine with the driving shaft 2 and the driving pulley 3. On the shaft 2 the partly cone-shaped drum 25 4 is fixed, bearing at its circumference the smoothing fingers 5. By means of pivots 6, the fingers, lying closely side by side, (Fig. 4) are fitted to levers or arms 7 and are individually kept in an upright position by springs 8. 9 are further springs which lie against the rear broad face 5^a of the backward extension of the smoothing fingers 5 as soon as these are put into action. 10 is a compound drum serving as a support for 35 the work-piece, the diameter of which may be altered according to the thickness of the leather by means of rings 11 which fit over one another. This compound drum 10 has a flange 12 in order to prevent the rings 40 and the leather from slipping off the drum. An adjusting fork 14 moved by rack and pinion 15 fits into the hub 13 of the drum 10, and serves to move the drum in axial direction on the shaft 2 according to the width of 45 the edge to be turned in.

On the shaft 16, which extends through the whole machine, a double lever 17 is fitted, bearing at its one end an ascending cam (guide) 18, and at its other end an elastic lever 19 with a pressure roll 20. The adjustment of the shaft is effected by the hand-wheel 16^a, which is fixed on the end of the shaft 16. If the lever 17 is brought in to the position shown in Fig. 2 the cam 55 18 exerts pressure on the spring 9 and therefore indirectly also on the smoothing fingers 5, which thereupon progressively move in a forward direction (Figs. 3 and 5) as the drum 4 is rotated. Owing to springs 9 the pressure exerted by the smoothing fingers on the leather is not absolutely firm, but somewhat of a yielding nature.

Immediately after the cam has passed, 60 the spring 8 causes each smoothing finger to quickly move back to normal position and

the spring 9 releases the rear face 5^a of the smoothing finger, so that the turned-in edge cannot be accidentally bent back.

If, however, lever 17 is brought into the position indicated in Fig. 4, the smoothing 70 fingers remain out of action in their normal position. In place, the roller 20 is put into working position on the drum 10.

The shaft 2 has a portion square in cross-section and on this portion there is a bevel pinion 21 with a sleeve 22, movable in axial direction. Into the sleeve fits a lever 23 which on the upper side has the form of a rack 24, sliding along a guide plate 25.

On shafts 26 and 27 are fixed the meshing 80 gears 29 and 28. Gear 29 engages rack 24. Shaft 27 and gear 28 can be adjusted by a hand-wheel 30. Beams 31 pass through the machine as a guide for the movable block 32 which carries the bearing for the shaft 33. 85 The block 32 has teeth 34 which engage the gear 28.

On the lower squared end of the shaft 33 is fixed an adjustable gear 34 engaging the bevel pinion 21. At the upper end of the 90 shaft 33 the circular cutter 36 and a bevel gear 37 are fixed. The circular cutter 36 always cooperates with the counter-cutter 38 on the shaft 39. The latter is hollow and of square section 40 (Fig. 2). Into this hollow 95 space fits the square end of the shaft 41, carrying a bevel gear 42 meshing with gear 37. Shaft 39 may be adjusted relative to 100 41 and fixed in any certain position (not shown), and is placed in the bearing 43 in the arm 44. The latter has a guide piece 45 fixed in the grooves 46 of the machine frame 1^a. The relative position can be adjusted from outside and has not been specially illustrated in Fig. 2. In this way, the arm 44 with the bearing 43 on the shaft 39 can be moved in the direction of the arrow 47. Near to the bearing 43 there is a stripping 105 device 48 which removes any small leather pieces, etc., adhering to the counter-cutter 38. 110

The circular cutter 36 can be continuously or intermittently ground by a grinding mechanism 49. This mechanism is, by means of the adjusting contrivances 50 and 51, fitted in the machine and adjusted in different directions. The grinding mechanism consists of the following parts: pulley 52, belt 53, pulley 54, shaft 55 with pulley 56, belt 57 and pulley 58, shaft 59, pulley 60, belt 61 and pulley 62. 49 is the grinding disc. 63 is one of the usual adhesive devices and 64 the leather piece to be turned in.

It has been found to be of advantage to fix a counter-guide 65 which guides the edge 64 before the smoothing fingers engage it. 125 Adhesive has already been applied to the edge, and therefore this guiding contrivance does not hinder the piece of work 64 in any way. This contrivance is also adjustable.

The drum and the smoothing fingers lie in 130

a protecting case 66. The smoothing fingers pass out through openings 67. An aperture 68 is provided through which the cam 18 projects into the case 66 when the parts are 5 in the position shown in Fig. 2.

Instead of the flange 12 (Fig. 1) of the drum 10 the roller 12^a (Fig. 4) can be used, as already mentioned. This roller can also be positively driven by teeth on the drum 10. 10 By means of this roller 12^a, it is very easy to manage concave curved parts. For this purpose, a canal 69 leads round the encased smoothing fingers, in which lies the piece of work. In order to remove the counter-cutter 38 when it is desired to change the circular cutter or the rings 11, I have found it to be of advantage to fit hinges 70 and 71, allowing the front parts 1^a and 1^b of the case to be swung open.

20 In Fig. 5 it will be easily seen that the edge 64^a of the leather piece 64 has, by means of a bending device (not shown) been lightly bent over. The smoothing fingers on the drum 4 gradually bend the edge sharply 25 and press same down. Immediately after, the irregular extreme edge 64^b of the leather on the support 39 is trimmed by the circular cutter 36.

The machine works as follows:

30 The skived and marked piece of leather is lead through the adhesive mechanism 63, from whence it passes a well-known preliminary bending device and on to the upper ring 11 of the drum 10. Now the smoothing 35 fingers guided by a cam 18 come down on the part of the turned-in leather edge nearest the flange 12 or the roller 12^a (Fig. 4). They then slide toward the free edge of the leather, the pressure exerted by the springs 40 gradually increasing. The somewhat over-stretched extreme edge of the leather is bent upward and reaches the rotating counter-cutter 38. Here the edge is trimmed by the circular cutter 36. As soon as each smoothing 45 finger reaches a position far forward, it slips off the cam and, owing to spring 8, restores to normal. It is now only necessary to press the turned-in edge firmly down with paper. The edge will be found perfect and 50 no further operation is necessary.

If it is desired to manufacture edging, to roll a skived edge thinner, or to roll down a closing seam, then it is only necessary to turn the shaft 16 by means of the 55 hand-wheel 16 (Fig. 4) in order to put the smoothing fingers out of action and to place the roller in working position. The width of the turned in edge and the width of the trimming can be regulated by moving the compound drum on the shaft 2 in axial direction by means of the regulating device 15. The same may be stated for the adjustment of the diameter of the drum by the rings 11, according to thickness of 60 leather. The manner of operation of the

other parts of the machine is the same as previously described.

It is to be understood that the invention is illustrated only by way of one example and that the scope of the invention is limited only by the claims hereunto appended. 70

Having described my invention, what I claim as new, and desire to secure by Letters Patent is:

1. In a machine of the class described, a 75 rotating drum forming a support for the material to be turned, a second drum rotating with the first named drum, smoothing fingers circumferentially arranged about said second drum and operable to gradually 80 turn and press an edge of said material, a cam for operating said fingers, and cooperating cutting elements for trimming said edge after it is turned.

2. In a machine of the class described, 85 a rotating drum forming a support for the material to be turned, a second drum rotating with the first named drum, smoothing fingers circumferentially arranged about said second drum and operable to gradually 90 turn and press an edge of said material, a cam for operating said fingers, a circular rotating cutter, and a counter-cutter cooperating with said rotating cutter to trim 95 said edge and act as a support for the same.

3. A machine in accordance with claim 1, wherein an adhesive-applying mechanism is provided through which the material is fed prior to its engagement with the first 100 named drum.

4. A machine in accordance with claim 1, characterized by movable arms carried by said second drum and to which said fingers are pivoted, and springs engaged with said 105 fingers to exert a yielding pressure thereagainst.

5. A machine in accordance with claim 1, characterized by movable arms carried by said second drum and to which said fingers are pivoted, springs engaged with said 110 fingers to exert a yielding pressure thereagainst, and other springs to restore said fingers to normal position when the latter are disengaged from said cam.

6. A machine in accordance with claim 1, characterized by an adjustable shaft on 115 which said cam is fixed, an arm supported by said shaft, and a roller carried by said arm and cooperating with the first named drum.

7. A machine in accordance with claim 1, wherein said first named drum is provided with a plurality of rings to permit of varying the diameter of the drum.

8. A machine in accordance with claim 1, wherein said first named drum is provided with a plurality of rings to permit of varying 125 the diameter of the drum, and a flange on said first named drum to prevent disengagement of the material therefrom.

9. A machine in accordance with claim 1, wherein said first named drum is provided with a plurality of rings to permit of varying the diameter of the drum, a flange on said first named drum to prevent disengagement of the material therefrom, and a roller associated with said first named drum to retain the material thereon while being turned.

10. In a machine of the class described, a rotating drum forming a support for the material to be turned, a shaft on which said drum is mounted, means to adjust said drum axially of said shaft, a second drum rotating with the first named drum, smoothing fingers circumferentially arranged about said second drum and operable to gradually turn and press an edge of said material, a cam for operating said fingers, and cooperating cutting elements for trimming said edge after it is turned.

11. In a machine of the class described, a rotating drum forming a support for the material to be turned, a second drum rotating with the first named drum, smoothing fingers circumferentially arranged about said second drum and operable to gradually turn and press an edge of said material, a cam for operating said fingers, a circular rotating cutter, a counter-cutter cooperating with said rotating cutter to trim said edge and act as a support for the same, and a stripper device for removing trimmings from said counter-cutter.

12. In a machine of the class described, a rotating drum forming a support for the

material to be turned, a second drum rotating with the first named drum, smoothing fingers circumferentially arranged about said second drum and operable to gradually turn and press an edge of said material, a cam for operating said fingers, cooperating cutting elements for trimming said edge after it is turned, and a casing for said fingers having an opening therein through which said cam projects.

13. A machine in accordance with claim 1, wherein said first named drum is provided with a plurality of rings to permit of varying the diameter of the drum, and wherein a casing is provided for the entire mechanism and formed with hinged closure members permitting access to said cutting elements and rings.

14. In a machine of the class described, a rotating drum forming a support for the material to be turned, a second drum rotating with the first named drum, smoothing fingers circumferentially arranged about said second drum and operable to gradually turn and press an edge of said material, a cam for operating said fingers, cooperating cutting elements for trimming said edge after it is turned, a casing for said fingers having an opening therein through which said cam projects, and a canal connected to said casing for receiving material of concave form.

In testimony whereof I have affixed my signature.

MAX KÖPPE.
